UNITED STATES PATENT OFFICE.

FREDERICK RATCLIFF, OF NEW BEDFORD, MASSACHUSETTS, ASSIGNOR TO
THE PAIRPOINT MANUFACTURING COMPANY, OF SAME PLACE.

DESIGN FOR A TRAY.

SPECIFICATION forming part of Design No. 23,114, dated March 13, 1891.

Application filed January 26, 1893. Serial No. 459,919. Term of patent 7 years.

To all whom it may concern:

Be it known that I, FREDERICK RATCLIFF, a citizen of the United States, residing at New Bedford, in the county of Bristol and State of Massachusetts, have invented and produced a new and original Design for Trays and other Articles, of which the following is a specification, reference being had to the accompanying drawings, showing the same.

Figure 1 is a top plan view of a tray showing my design and Fig. 2 a sectional view on line 2—2 of Fig. 1.

The leading feature of my design is a tray of greater length than breadth and dished in cross-section having a name space upon the

upper surface of its bottom and upon the name space a raised pen.

A is the upper surface of the bottom of the tray which is dished in cross-section (see Fig. 2) and this portion A forms a name-space 20 within the raised margin of the tray.

D is a raised pen upon the surface of the name space.

What I claim is—

The design for a tray herein shown and described.

FREDERICK RATCLIFF.
